ELECTRIC MOTOR

Joseph E. Baclawski, Fort Wayne, Ind., assignor to General Electric Company, a corporation of New York

Filed Dec. 17, 1962, Ser. No. 72,870

Term of patent 14 years

(Cl. D26—5)

Fig. 1.

Fig. 2.

FIG. 1 is a side and end perspective view of an electric motor, showing my new design; and

FIG. 2 is an opposite end elevational view thereof. The sides not shown have substantially the same appearance as the side shown in FIG. 1.

The dominant features of my new design are shown in solid lines in the drawing.

I claim:

The ornamental design for an electric motor, substantially as shown and described.
